(57) **CLAIM**

The ornamental design for a storage container, substantially as shown and described.

DESCRIPTION

FIG. 1 is a perspective view of a storage container according to an embodiment of the design, in a doors-closed configuration.

FIG. 2 is a front view of the storage container of FIG. 1.

FIG. 3 is a back view of the storage container of FIG. 1.

FIG. 4 is a first side view of the storage container of FIG. 1.

FIG. 5 is a second side view of the storage container of FIG. 1.

FIG. 6 is a top view of the storage container of FIG. 1.

FIG. 7 is a bottom view of the storage container of FIG. 1.

FIG. 8 is another perspective view of the storage container of FIG. 1, in a doors-open configuration.

FIG. 9 is a front view of the storage container of FIG. 8.

FIG. 10 is a back view of the storage container of FIG. 8.

FIG. 11 is a first side view of the storage container of FIG. 8.

FIG. 12 is a second side view of the storage container of FIG. 8.

FIG. 13 is a top view of the storage container of FIG. 8; and,

FIG. 14 is a bottom view of the storage container of FIG. 8.

In the drawings, the broken lines depict environmental subject matter only and form no part of the claimed design. The drawings include symbolic break lines. Any portion of the storage container between the break lines forms no part of the claimed design.
